US00D632770S

(12) **United States Design Patent**
Rotter et al.

(10) **Patent No.:** **US D632,770 S**
(45) **Date of Patent:** ** *Feb. 15, 2011

(54) **CYCLONIC AIR CLEANER HOUSING**

(75) Inventors: **Terrence M. Rotter**, Sheboygan Falls, WI (US); **Jeffrey S. Sayler**, Howards Grove, WI (US); **Richard R. Koehl**, Sheboygan, WI (US); **Robert J. Hensel**, Germantown, WI (US); **Herbert V. Kohler, Jr.**, Kohler, WI (US)

Primary Examiner—David G Muller(74) *Attorney, Agent, or Firm*—Whyte Hirschboeck Dudek S.C.(57) **CLAIM**

An ornamental design for cyclonic air cleaner housing.

DESCRIPTION

FIG. 1 is a perspective view of an embodiment of a cyclonic air cleaner housing;

FIG. 2 is a front view thereof;

FIG. 3 is a right side view thereof;

FIG. 4 is a left side view thereof;

FIG. 5 is top view thereof;

FIG. 6 is a rear view thereof; and,

FIG. 7 is a bottom view thereof.

The broken lines shown in the figures are for illustrative environmental purposes only and form no part of the claimed design.
